UNITED STATES PATENT OFFICE

LOUIS C. WALKER, OF DAYTON, OHIO

PASS BOOK

Application filed April 25, 1928. Serial No. 272,753.

My invention relates to printing and book making, and more particularly, to the manufacture of pass books for the use of banks, loan companies, installment sales institutions, 5 and the like.

Within recent years there has come into extensive use registering and accounting machines for entering upon pass books and simultaneously upon corresponding record or 10 account cards amounts of deposit, withdrawal, payments, purchase, or the like. In the use of such registering and accounting mechanism the customer's pass book and the record card of the bank or merchant are simultaneously inserted in the machine and duplicate typed imprints are made thereon. It is therefore essential that the pass book correspond exactly with the record or account card in order that the imprint shall be made in like 15 position upon the respective pass book and card. Much difficulty has been experienced in the use of bound or sewed books, since the attachment of the leaves in the fold of the back tends to produce a welt or unevenness 20 which interferes with the insertion and removal of the book and also interferes with the production of clean cut and clear impressions of the recording type in positions close to the fold of the leaves. These pass books 25 are ordinarily small, having but few leaves. It is necessary however, that the printing on opposite sides of the leaves shall be accurately registered and in the gathering of the leaves it is necessary that the printing upon 30 one leaf shall register exactly with that on the succeeding leaf.

In the present instance a flat opening book, having accurately registered imprint spaces on opposite sides of the leaves and upon succeeding leaves to receive the machine typed entries of deposits, withdrawals, payments or purchases is produced by printing the entry spaces in a single operation on one side only of an elongated strip which is subsequently 40 folded upon itself reversely into "fan-fold" formation, the alternating folds being interconnected by pasting the unprinted rear face of such strip together at intervals, thereby forming leaves of double thickness with final 45 leaves comprising the ends of the printed 50

strip forming leaves of single thickness, one of which is pasted to the inner surface of the cover sheet for lining and for stiffening purposes.

The printing of opposite sides of succeeding pages simultaneously upon a continuous surface insures accurate registry, and also permits flat opening of the book. 55

The object of the invention is to simplify the construction of flat opening pass books, 60 and the like, whereby they will not only be cheapened in construction, but, whereby the printed registration faces of the book will be in proper registry with each other, and whereby the book may be printed and assembled with minimum labor and expense. 65

A further object of the invention is to provide a pass book, or the like, which will open flat without an obstruction, offset or shoulder at the fold of the book which will interfere 70 with its insertion into a registering or imprinting machine.

With the above primary and other incidental objects in view, as will more fully appear in the specification, the invention consists of the features of construction, the parts and combinations thereof, and the mode of operation, or their equivalents, as hereinafter described and set forth in the 75 claims. 80

Referring to the accompanying drawings, wherein is shown the preferred, but obviously not necessarily the only form of embodiment of the invention, Fig. 1 is a perspective view of the pass book forming the subject matter hereof and of the record card with which such pass book must agree. Fig. 2 is a view of the printed sheet in extended form from which the pages are formed by folding. Fig. 3 is a detail end view of the book showing the manner of folding and pasting the sections of the strip to form successive leaves. 85 90 95

Like parts are indicated by similar characters of reference throughout the several views.

Books of the present type are usually quite small, consisting of but four pages to receive imprint entries. For illustrative 100

purposes the book has been shown with an additional leaf, thus affording six pages.

Obviously, within a limited range the book may be provided with different numbers of leaves. The predominating idea, however, is that these pages of whatever number, are simultaneously printed at a single impression, thereby insuring accuracy of registry and obviating the necessity of gathering separately printed leaves.

Referring to the drawings, there is shown in Fig. 2 the elongated strip 1 having imprinted on one side thereof the form of a succession of pages. This printing is done at a single impression. The strip 1 is folded reversely at spaced intervals as indicated at 2 and 3. The reverse side of the strip 1 is plain. The plain sides of these successive folds are united by pasting or gluing to form one or more leaves 4 of double thickness, which will bear on their opposite faces or pages successive sections of the printed impression. These leaves of double thickness may be pasted or glued throughout their entire area, but for economy of manufacture and simplicity of assembly the folded sections comprising each double thickness leaf are preferably united on narrow strips 5 adjacent to the inner fold 2. The successive folds 2 and 3 of the printed strip 1 are in such direction that the terminal sections or pages 6 are of single thickness. The back or cover of the book consists of a single continuous sheet of paper, fabric, or the like, cut to size and medially folded to agree with the size of the leaves 4 and 6 formed from the printed strip. One of the end leaves 6 is pasted to the inner face of one of the folded half sections of the cover sheet 7. This printed page form 6 of single thickness thus forms a lining and reinforcement for the book cover 7 and furthermore serves to attach thereto in proper relation the succeeding leaves of double thickness formed by united folds of the printed strip. The final page form 6 of the printed strip may be similarly glued or pasted to the inner face of the opposite back section 7 or it may be left loose as shown in Fig. 1, and an independent folded sheet 8 may have one portion glued to the inner face of the second section of the back or cover 7 while the other portion extends free as a fly leaf 9. These last mentioned leaves may contain printed matter such as the rules of the institution, directions concerning the making of deposits and withdrawals or contract as to payments, etc.

Obviously, this printed matter may be included upon the terminal page forms of the original strip 1 and so contained upon one of the leaves of double thickness.

Record folders have heretofore been devised and used wherein a fan-fold or bellows strip is employed, which may be extended to full length and refolded between the covers

of the folder. However, such strip is inconvenient to use and is quite likely to become torn or mutilated and furthermore, is not susceptible of convenient operation in a register or accounting mechanism for which the present book is designed. The present construction affords all of the advantages of the ordinary pass book from which have been eliminated the objectionable features of the welt or raised bead forming the back of the book, which when opened flat, forms an obstruction to its insertion within the register, and facilitates proper registration between the imprints upon succeeding pages. The record card 10 with which this book is ordinarily employed contains an imprinted record agreeing exactly with that of the book pages. The operation of imprinting the amounts of deposits, withdrawals or payments in the book also effects the same imprinted record upon the card. For this reason accuracy of registration is an important factor.

From the above description it will be apparent that there is thus provided a construction of the character described possessing the particular features of advantage before enumerated as desirable but which construction obviously is susceptible of modification in its form, proportions and arrangement of parts, without departing from the principle involved or sacrificing any of its advantages.

While in order to comply with the statute the invention is described in language more or less specific as to structural features it is to be understood that the invention is not limited to the specific details shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. An account book comprising a flexible record strip having thereon a single printed impression comprising a succession of page forms appearing on one side only of the strip, said strip being transversely folded, the adjacent faces of adjacent folds being permanently attached together to form a leaf of double thickness, the opposite faces of which comprise successive page forms, the terminal section of said folded strip being of single thickness and a folded cover portion to the inside face of one half section of which the terminal leaf of single thickness is permanently attached throughout to form a reinforcement lining and to secure said double thickness leaf to the cover independent of other attachment means.

2. In an account book, a filler portion including a leaf of double thickness and preceding and succeeding leaves of single thick-

ness integral with the leaf of double thickness, and a cover therefor comprising a medially folded section of material to the inner face of one half section of which one of said leaves of 5 single thickness is attached in such relation that the hinge folds of said integral leaves coincide with the fold of the cover section.

3. As an article of manufacture, an account book filler comprising a continuous strip of 10 record material having page form imprints on one side thereof, said strip being alternately folded at spaced intervals, the first fold of which is in the direction of the printed side which shall form the interior faces of the 15 first fold, the interior faces of alternate folds comprising the reverse side of the printed strip being fixedly attached to each other to form leaves of double thickness and a terminal leaf of single thickness.

20 4. The herein described method of forming an account book filler consisting in printing upon one side of an elongated strip a succession of page forms and reversely folding the sheet at spaced intervals, the first fold 25 being disposed with the page forms interiorly of the fold and permanently attaching the reverse sides of the succeeding page forms together in pairs to form a leaf of double thickness having page forms on its opposite 30 faces.

5. The herein described method of forming a flat opening book consisting in printing a succession of page forms on one side of a continuous strip, reversely folding the 35 strip at intervals, the first fold from the end of the strip being directed with the printed page forms interiorly of the fold and forming leaves of additional thickness by permanently attaching the reverse sides of succeeding 40 page forms comprising the interior faces of succeeding folds one to the other in pairs, and attaching the reverse side of the initial page form to the inner face of one half section of a folded cover.

45 In testimony whereof, I have hereunto set my hand this 13th day of April, A. D. 1928.

LOUIS C. WALKER.
